Patented Apr. 30, 1918.

FIG. 1.

FIG. 2.

INVENTOR
ALFRED G. BROWN
Hazard & Miller
1918

UNITED STATES PATENT OFFICE.

ALFRED G. BROWN, OF LOS ANGELES, CALIFORNIA.

VEGETABLE-FIBER SCUTCHING, HECKLING, AND CLEANING MACHINE.

1,264,608.

Specification of Letters Patent. Patented Apr. 30, 1918.

Application filed June 21, 1917. Serial No. 176,121.

To all whom it may concern:

Be it known that I, ALFRED G. BROWN, a citizen of the United States, residing at Los Angeles, in the county of Los Angeles 5 and State of California, have invented new and useful Improvements in Vegetable-Fiber Scutching, Heckling, and Cleaning Machines, of which the following is a specification.

10 This invention relates to vegetable fiber treating machinery and particularly pertains to a scutching, heckling and cleaning machine.

It is the principal object of this invention 15 to provide a machine of a simple nature which may be easily operated to scutch, heckle and clean vegetable fiber, such as the leaves of yucca plant and other vegetable material.

20 Another object of this invention is to provide a machine which may be readily adjusted to accommodate material of various thicknesses and lengths and will thoroughly scutch and heckle it so that it may thereafter 25 be used for the making of rope, twine and other articles of manufacture.

It is a further object of this invention to provide a machine of the above character composed of a few simply designed elements 30 adapted to be easily manufactured, and which are not liable to become broken, or otherwise render the apparatus inoperative.

Other objects will appear hereinafter.

The invention is illustrated, by way of 35 example, in the accompanying drawings in which:

Figure 1 is a view in side elevation illustrating the complete machine and particularly disclosing the relation of the scutching drums to each other.

Fig. 2 is a view in end elevation illustrating the drums and their clothing.

Referring more particularly to the drawings, 10 indicates a base upon which are mounted bearing uprights 11 and 12. These posts are secured in spaced relation to each other upon the base and are held together by a transverse frame member. The vertical supports 11 and 12 may also be suitably 45 braced to form an adequate supporting structure for scutching drums 13 and 14. The drums are made in duplicate and are mounted separately upon vertically aligned mandrels 15 and 16. The mandrels extend 50 outwardly from the large ends of the scutching drums and are housed within suitable 55 bearings, the lower mandrel 16 being thereby secured within a fixed bearing mounted between the vertical supports. The upper mandrel is rotatably mounted within a box 60 17 which is positioned between parallel vertical ways secured between the uprights. This box is adapted to be adjusted vertically by means of an adjusting screw 18 which is connected in a rotatable manner to the top 65 of the box and extend through screw bushings 19 mounted in the upper transverse frame. A hand wheel 20 is fixed at the top of the screw and permits it to be rotated to raise and lower the box. Mounted upon 70 each of the shafts and adapted to mesh with each other are spur expansion gears 21 and 22 which insure that the two shafts will rotate simultaneously in opposite directions and at the same speed when the shaft 16 is 75 driven by means of the pulley 23 secured thereupon.

The scutching elements have main central drums 24 and 24' and extension cones 24^a and 24^b, which are concentrically mounted 80 upon the shafts 15 and 16. The main portions of these drums are cylindrical and have longitudinally straight side walls and the extension walls converge at the ends opposite the driving gears to produce the frusto-conical bodies 24^a and 24^b tapering toward the drum ends. Each drum, formed as described, provides a mounting for a series 85 of scutching members 25 and cleaning pins 26. The scutching members extend the 90 length of the drums 24 and 24' and are spaced in relation to each other transversely. These members preferably are of angle irons, corresponding flanges of which are secured 95 by bolts 27 to the face of the drum, while the other flanges extend radially therefrom and form scutching blades. The outer edges 100 of the scutching blades have a series of serrations formed along them which provide square teeth 24^c having square gullets and straight sides, although they may be made without serrations, if desired. The ends 105 24^c of the teeth are blunt and of a width equal to the width of the blade. An examination of Fig. 1 will disclose the fact that these 110 teeth 24^c extend only the length of the straight cylindrical portions 24 and 24' of the drums and that smooth blades 24^c are then formed with convexed portions having a radius somewhat greater than the diameter of the drum. These convexed blade portions are arranged along the inclined end

portions of the drums and form a feeding throat 28 which permit the leaves of the plants to be fed into the toothed portions of the drums. It is to be further noted that 5 the teeth 24^e upon the various scutching blades are staggered in relation to each other and are also staggered in relation to the teeth upon the opposite scutching drum, care being taken to cause the blades upon the 10 two drums to coincide with each other in their paths of travel so that the leaves of the plants will be subjected to a combined action of the two blades as they pass toward and away from each other. Interposed between 15 the various scutching elements are the sets of the cleaning pins 26. These pins are radially arranged upon the drum and terminate substantially along the circumferential plane described by the outer faces of the 20 scutching blades. These teeth are mounted upon suitable plates 29 held by bolts 30 to the outer cylindrical face portion of the drums. A pair of guard boards 31 and 32 are secured upon the frame along the operating 25 side and are spaced from each other, as particularly shown in the drawings, to form a throat 33 and an elongated slot 34, through both of which the leaves are fed.

In operation, the pulley is driven by a belt 30 which transmits power from a suitable driving mechanism. The rotation of this pulley will simultaneously drive shafts 15 and 16 through the medium of the gears 21 and 22 and in the directions indicated by the arrows —a— and —b—. The leaves of the 35 yucca, or other fibrous material is then thrown between the guard boards 31 and 32 and into engagement with the rotating scutching drums. The operator holds to the 40 ends of the leaves and swings them horizontally into the throat 28 at the right-hand end of the drums. The leaves are firmly held by the operator and the blades and pins allowed to tear through them, thus heckling 45 and scutching them. This operation may be continued until the ends are thoroughly scutched, after which the leaves may be inverted and the opposite ends treated in a similar manner. The action of the blunt 50 square edged teeth will scutch the fiber and heckle it while the cleaning pins 26 will act to further clean and part the fibers. In case leaves of large dimension are being fed through the machine, the drums may be 55 slightly separated to form a larger throat and greater space between the members.

It will thus be seen that by the use of this device, fibrous vegetable material may be thoroughly separated and a scutching action

produced which will provide fiber suitable 60 for various manufacturing purposes.

While I have shown the preferred construction of my vegetable fiber scutching, heckling and cleaning machine as now known to me, it will be understood that various 65 changes in the combination, construction and arrangement of parts, more particularly the scutching and heckling bars, teeth and cylinder clothing, may be made by those skilled in the art without departing from the 70 spirit of my invention.

I claim:

1. A scutching and heckling machine, comprising a frame, a pair of parallel horizontal shafts, means whereby said shafts 75 may be rotated in opposite directions to each other, drums secured upon said shafts, said drums having a cylindrical portion and one tapered end, blades mounted upon the drum and spaced therearound, said blades 80 extending longitudinally of the cylindrical and tapered portions of the drum, teeth formed upon the portion of the blades extending along the cylindrical part of the drum, said teeth having square blunt ends 85 and straight sides, and smooth convexed faces formed upon the blades extending along the tapered portion of the drums whereby a throat will be formed between and at one end of the drums and will cause 90 the fibrous vegetable material to be drawn into the toothed portions of the blades.

2. A scutching and heckling machine, comprising a frame, a pair of parallel horizontal shafts, means whereby said shafts 95 may be rotated in opposite directions to each other, drums secured upon said shafts, said drums having a cylindrical portion and one tapered end, blades mounted upon the drum and spaced therearound, said blades extending longitudinally of the cylindrical and tapered portions of the drum, teeth formed upon the portion of the blades extending along the cylindrical part of the drum, said teeth having square blunt ends and straight 100 sides, smooth convexed faces formed upon the blades extending along the tapered portion of the drums whereby a throat will be formed between and at one end of the drums and will cause the fibrous vegetable material 105 to be fed into the toothed portions of the blades, and radially extending pins interposed between said blades and adapted to act upon the fibrous material.

In testimony whereof I have signed my 115 name to this specification.

ALFRED G. BROWN.
